MODULATING MEANS

George L. Usselman, Port Jefferson, N. Y., assignor to Radio Corporation of America, a corporation of Delaware

Application September 20, 1932, Serial No. 633,955

23 Claims. (Cl. 179—171)

This invention relates to signalling means and in particular to means whereby the characteristics of high frequency oscillations other than amplitude are varied in accordance with signals to be transmitted.

It has been found that ordinary amplitude modulated high frequency oscillations in transmission from the sending station to the receiving station are subject to what is known as fading effects. This is a decided disadvantage since it introduces drop-outs and errors in the signal. Even where diversity receivers are used to receive the amplitude modulated signals the effect of fading is of serious disadvantage.

I have found that if the high frequency oscillations are modulated in phase or in frequency in accordance with the signal to be transmitted they are less subject to the effect of fading than amplitude modulated waves. The reason why phase or frequency modulated oscillations in transmission are subject to a less extent to fading effects than oscillations modulated otherwise is that a greater amount of the transmitter power is available for transmission. In other words, a transmitter can operate at full output in phase or frequency modulation while it is necessary to reduce the power output to about one-quarter for amplitude modulation. Assuming equal power output, reduction of fading may be slightly greater in phase or frequency modulation than in other kinds of modulation.

In each of my United States applications, Serial No. 623,558, filed July 20, 1932; Serial No. 616,026, filed June 8, 1932, Patent #2,036,165, dated March 31, 1936; Serial No. 602,487, filed April 1, 1932; and Serial No. 607,932, filed April 28, 1932, Patent #2,036,164, dated March 1, 1936, I have shown means for varying at signal frequency the characteristics other than the amplitude of a carrier frequency. In each of these arrangements the carrier frequency is impressed substantially cophasally on to the control grids of a pair of thermionic tubes which have their anodes connected in parallel to a common tank circuit and their internal impedances varied in phase opposition by the signal wave. In each of these arrangements the phase modulator stage comprises two tubes.

The present invention relates to an improved modulating means broadly of the type referred to above.

More in detail, this invention relates to an improved modulating means wherein the modulator stage comprises but a single tube and wherein

an efficient means is provided whereby variations in phase or frequency of a carrier wave at signal frequency are accomplished.

The novel features of my invention have been pointed out with particularity in the claims appended hereto.

The nature of my invention and the operation thereof will be best understood from the following detailed description thereof and therefrom when read in connection with the drawings, throughout which like reference numerals indicate like parts, and in which:

Figure 1 illustrates a specific embodiment of the invention; while

Figures 2, 3 and 4 illustrate modifications of the arrangement of Figure 1.

A specific embodiment of my present invention is shown in Figure 1. This transmitter consists of the following stages and circuit. A substantially constant frequency oscillator A generates the carrier frequency and delivers it to a tuned tank circuit E comprising a tuning capacity 1 and an inductance 2. The midtap of the inductance coil 2 of the tank circuit E is grounded for radio frequency by connecting the same through the by-pass condenser C₁ to ground. Tank circuits F and G are each inductively coupled to tank circuit E through inductance coils 16 and 15 respectively and variably inductively related to inductance 2 of tank circuit E. Tank circuit F is composed of inductance coil 16, fixed condenser 14, resistor 12, and variable tuning capacity 18; while tank circuit G is composed of coil 15, fixed condenser 13, resistor 11, and variable tuning capacity 17. Tank circuit F is grounded at one end for radio frequency oscillations by a lead connected between condenser 14 and resistor 12 through by-pass condenser 27 to the grounded filament lead FL. Tank circuit G is grounded for radio frequency oscillations by the same lead connected between condenser 13 and resistor 11 through by-pass condenser 27 to the grounded filament lead FL. These points on each tank circuit are also connected by way of lead 32 to the positive terminal of the power supply 26.

Tubes I and J are the amplitude modulator tubes. The anode electrode 10 of tube I is connected to the tank circuit F at a point between resistor 12 and variable condenser 18, while the anode 9 of tube J is connected to the tank circuit G at a point between resistor 11 and variable condenser 17. Control grids 7 and 8 of tubes J and I are connected in phase opposition to the secondary winding 19 of transformer T₁. 55

Parasitic prevention resistors 3 and 4 are inserted in the connections between the terminals of the winding 2 and the control grids 7 and 8 respectively. These resistors are also grounded at the ends adjacent winding 19 for radio frequency by connecting said ends through by-pass condensers 5 and 6 to the grounded filament lead FL, as shown. The midpoint of the secondary winding 19 of transformer T₁ is connected by lead GB to a point on the potentiometer P₁ connected in parallel with a portion of the source of direct current 26. In this manner negative bias of the desired potential may be applied constantly to the control electrodes 7 and 8 of tubes J and I. The primary winding of transformer T₁ is connected to a source of signal frequency B as shown. Cathodes 20 and 21 of tubes I and J are connected to the power supply circuit FL, which is in turn connected with a portion of source 26, as shown.

One end of phase retarding element L is connected to tank circuit F at a point between inductance coil 16 and variable condenser 18, and likewise one end of phase advancing element M is connected to tank circuit G at a point between inductance coil 15 and variable condenser 17. The other ends of both phase shifting elements L and M are connected together and are also connected through blocking condenser 22 to the control grid 24 of thermionic modulator tube K. Tube K and tank circuit H comprising tuning capacity 31 and inductance 32 is the phase modulator stage. Control grid 24 of tube K is supplied with steady negative bias from the power source 26, through the resistor 23 and lead 33, which is connected to a movable point on potentiometer resistance P₂. The lower end of resistor 23 is grounded for radio frequency currents through the by-pass condenser 28 as shown. The anode 25 of tube K is connected, as shown, to the top of tank circuit H. Charging potential is supplied to anode 25 from source 26 through the inductance coil 32 of tank circuit H and lead 34. The lower end of tank circuit H is grounded for radio frequency oscillations through the by-pass condenser 29, as shown in Figure 1.

Tube K is shown as the screen grid type but a three element tube may be used by providing grid neutralizing arrangements. Charging potential for the screen grid electrode 35 of tube K is supplied by way of lead 36 from a potentiometer P₂ connected in parallel with direct current source 26. Any radio frequency oscillations reaching the screen grid electrode 35 are shunted around source 26 by by-pass condenser 37.

The tank circuit H is connected to the stage C through a line including blocking condenser 30. Stage C may contain amplitude limiters, frequency multipliers and amplifiers, or any combination of the three. The output stage of C is connected to a load circuit, which, in this case, is shown as antenna D.

To describe the operation of this invention, assume that oscillator A is delivering carrier energy of substantially constant frequency and amplitude to tank circuit E. Now tank circuits F and G are both inductively coupled, by variable means, to tank circuit E. It should be stated here that coils 15 and 16 are wound in the proper direction to excite both phase shifting elements L and M cophasally. Tank circuits F and G are tuned to the frequency of oscillator A by the variable condensers 18 and 17

respectively. Note also that the coupling between inductance coils 16 and 15 and inductance 2 of tank circuit E is adjusted to a value such that energy of equal amplitude is impressed on to the tank circuits f and g.

Now, if there is no signal present, the excitation energies reaching the control grid 24 of tube K from source A by way of tank circuits F and G will be of equal amplitude. This follows if it is assumed that the impedances of phase shifting elements L and M to the high frequency oscillations from A are equal, which they should be. The phase of the carrier energies reaching 24 from tank circuits F and G will be shifted in opposite directions relative to an average phase value by the phase shifting elements L and M. When there is no signal the resultant excitation energy applied to the control electrode 24 will have a constant phase angle which will be half way between the extreme limits of the modulating angle. Tank circuit H may be tuned by capacity 31 to the frequency of the source A or to a harmonic of said frequency, in which case the phase modulator stage K will either amplify or multiply the oscillations from A. This carrier energy in tank circuit H then may be either amplitude limited, or frequency multiplied, or amplified, or any one or more of said operations may be carried out in stage C before the energy is radiated by antenna D.

Now, if we assume that signal frequency is being sent out from source B, it will be transmitted through transformer T₁ to the grids 7 and 8 of tubes J and I. The signal from B may consist of alternating voltages of variable amplitudes. Suppose an instant be taken in the signal operation when control grid 7 is driven positive by signal voltages from B and the control grid 8 is driven negative by signal voltages from B. At this instant anode electrode 9 of tube J will carry more direct current than will anode electrode 10 of tube I. Therefore, the alternating current resistance of tube J will be lower than the alternating current resistance of tube I. Now you will note from Figure 1 that the anode to cathode impedance of tube J is, in effect, connected in parallel with resistor 11 of tank circuit G, while the anode to cathode impedance of tube I is, in effect, connected in parallel with resistor 12 of tank circuit F. Since the internal impedance of tube J has been reduced by the signal and also the anode to cathode impedance of tube I has been increased by the signal, the total resistance in tank circuit G is consequently reduced while the total resistance in tank circuit F is increased. This causes an increase in the amplitude of the carrier voltage in tank circuit G and a corresponding decrease in the amplitude of the carrier voltage in tank circuit F.

The carrier energy reaching the grid 24 of the tube K from the tank circuit G will be increased a certain amount while the carrier energy reaching grid 24 from tank circuit F will be decreased by the same amount. Taking into account the phase shift of the carrier voltages delivered by circuits G and F, through the phase shifting elements M and L, the resultant excitation voltage amplitude is constant but the phase angle of the resultant has shifted. In this case it has been advanced in phase. It can be shown by vector analysis that, as tubes J and I are differentially amplitude modulated, the total excitation energy reaching grid 24 is constant but of changing phase angle. The frequency of this phase modu-

lation will be the signal frequency and the degree of phase modulation will be proportional to the intensity or amplitude of the signal. The limit of the amount of phase modulation possible can 5 be set by adjusting the capacity of condenser M and by adjusting the inductance of coil L. The characteristics of the resultant excitation on grid 24 are transmitted on through the various stages, in which the phase modulated carrier may be 10 amplified or multiplied in frequency, or both. Any undesirable amplitude modulation may be eliminated by limiting circuits and the carrier may be further amplified and multiplied in frequency before it is radiated by antenna D. When 15 the carrier frequency is multiplied, the amount of phase modulation is increased in the same ratio.

In practice the phase shifting means L and M may each comprise a variable capacity and inductance in series, as illustrated in Figure 2, wherein the improved phase or frequency modulator is otherwise the same as the arrangement of Figure 1. Moreover, the phase shifting elements L and M of Figures 1 and 2 may, where desired, 25 be replaced by lines or conductors of different electrical length to obtain the desired phase shift. The use of such lines of different electrical length has been disclosed by me heretofore in my United States application Serial No. 607,932, filed April 30 28, 1932, Patent #2,036,164, dated March 31, 1936.

The operation of the arrangement of Figure 2 is the same as the arrangement of Figure 1.

In the arrangement of Figure 3 the phase shifting elements L and M have been replaced by ohmic resistances R_2 and R_3 respectively. These resistances do not cause a phase shift in the carrier frequency energy applied to the control electrode 24 by way of tank circuits F and G. In order to obtain the necessary phase shift in the 40 carrier frequency energy applied by way of tank circuit F and G, I tune one of the circuits to a frequency slightly above resonance, that is, above the frequency of the oscillations introduced from A by way of tank circuit E to tank circuits F and 45 G, and detune the other circuit, that is, tune the other circuit to a point slightly below resonance, or below the frequency of the oscillations reaching the circuits F and G, from A by way of tank circuit E. More specifically, the tank circuit F 50 may be tuned to a frequency $f+f_1$ where f is the resonant frequency, or frequency of the tank circuit E, and f_1 is in increment sufficient to obtain the desired phase shift of the carrier energy. The tank circuit G may be tuned to a frequency 55 $f-f_1$. Here again f is the frequency to which the tank circuit E is tuned and f_1 is in increment in frequency sufficient to apply to the carrier frequency leaving the tank circuit G the desired phase shift. The total impedance of circuits F 60 and G will depend here, as in Figure 1, on the impedance between the anodes and cathodes of tubes I and J. This impedance in turn depends on the signal potential applied to I and J from T₁.

The modification shown in Figure 3 is otherwise similar to the arrangement of Figure 1. Moreover, the operation of the arrangement of Figure 3 is the same as the operation of the arrangement of Figure 1, except as otherwise hereinbefore noted. The phase retarded oscillations 0 of tank circuit F are applied by way of ohmic resistance R_2 to the control electrode 24 of tube K, while the phase advanced oscillations of tank circuit G are applied by way of ohmic resistance R_3 to the control electrode 24 of phase or frequency modulator K.

In all of the modifications shown above the tank circuit H may be tuned either to the fundamental frequency, that is, to the frequency of the oscillations from A, or it may be tuned to any harmonic of the frequency of the oscillations 5 from A.

Where desired the tank circuits F and G may be coupled to tank circuit E through capacities, as indicated in Figure 4, rather than by way of inductive coupling, as shown in Figure 1, or the 10 tank circuits F and G may be coupled to tank circuit E capacitively and inductively, as shown in Figures 1 and 4.

The capacities 40, 41 may be fixed and connected, as shown, by variable taps to the inductances 2 and 16 and 15 or the capacities may be 15 variable and connected, as shown, to movable points or to fixed points on said inductances.

The arrangement of Figure 4 is otherwise the same as the arrangement of Figure 1. Moreover, the operation of the device of Figure 4 is so like the operation of the arrangement of Figure 1 that it is thought unnecessary to repeat said operation at this point.

Having thus described my invention and the 25 operation thereof, what I claim is:

1. The combination of a source of high frequency oscillations, a thermionic modulator tube, a pair of tank circuits coupled to said source, a connection between each of said tank circuits 30 and said tube, a fixed resistance and a variable resistance in each of said tank circuits, and means for varying said variable resistances at signal frequency to produce phase modulation of the oscillations from said source. 35

2. The combination of a source of high frequency oscillations and a thermionic modulator tube, of a pair of tank circuits coupled to said source, means for tuning each tank circuit to a different frequency, a variable resistance in each 40 of said tank circuits, impedances of similar character connecting each tank circuit to the control electrode of said tube, and circuits for varying said resistances at signal frequency.

3. Means for modulating the phase of oscillations from a source of high frequency oscillations comprising, a thermionic modulator tube, a pair of tuned tank circuits coupled to said source of oscillations, a fixed resistance and a variable resistance in parallel in each of said tank circuits, 50 phase shifting impedances connecting said tank circuits to the input electrode of said tube, and means for varying said variable resistances at signal frequency.

4. Phase modulated wave producing means to be 55 used with a source of high frequency oscillations comprising, a thermionic tube, a pair of tank circuits interposed between said source of high frequency oscillations and the control electrode of said tube, a resistance in each of said tank circuits, a thermionic impedance connected in parallel with each of said resistances and means for varying said thermionic impedance at signal frequency.

5. Means for varying the phase of high frequency oscillations from a source of high frequency oscillations comprising, a thermionic tube, a pair of tank circuits connected thereto, symmetrical means for coupling said source of high frequency oscillations to said tank circuits, tuning 70 means for each tank circuit, a resistance in each of said tank circuits, a thermionic impedance connected in parallel with each of said resistances, and circuit for varying said thermionic impedances oppositely in accordance with signals. 75

6. The combination of a source of high frequency oscillations, a tank circuit connected thereto, a thermionic tube, a pair of tank circuits symmetrically coupled to said source of high frequency oscillations, a pair of thermionic tubes, means for connecting the internal impedance of one of said pair of tubes in one of said tank circuits, means for connecting the internal impedance of the other of said tubes in the other of said pair of tank circuits, phase shifting elements of different characteristics for coupling each tank circuit to the control electrode of said first named thermionic tube, and a source of signal potentials coupled to an electrode in each of 15 said pair of thermionic tubes.
7. Phase modulating means comprising, a thermionic tube adapted to repeat high frequency oscillations, a pair of tank circuits tuned to different frequencies and responsive to high frequency oscillations, resistances connecting each of said tank circuits to the input electrodes of said tube, a fixed impedance in each of said tank circuits, a variable impedance connected in parallel with each of said fixed impedances, and means for 20 varying oppositely the impedances of said variable impedances at signal frequency.
8. Signal modulating means comprising, a thermionic tube adapted to repeat high frequency oscillations, a pair of tank circuits responsive to high frequency oscillations, means for tuning said tank circuits to different frequencies, impedances connecting each of said tank circuits to the input electrodes of said tube, a pair of thermionic tubes, means for connecting the internal impedance of one of said tube in one of said tank circuits and of the other of said tubes in the other of said tank circuits, and means for varying the impedances of said tubes at signal frequency.
9. Means for modulating high frequency oscillations comprising, a thermionic modulator, a pair of tuned tank circuits, means for impressing high frequency oscillations symmetrically on said tank circuits, impedances connecting each of said tank circuits to the control electrode of said tube, a pair of thermionic tubes, means for connecting the impedance of each of said thermionic tubes in series with a different one of said tank circuits, and means for varying in phase opposition at signal frequency the impedances of said tubes.
10. A phase or frequency modulator comprising, a thermionic modulator tube, a source of high frequency oscillations, a pair of tank circuits symmetrically coupled to said high frequency source of oscillations, phase shifting means interposed between each of said tank circuits and the control electrode of said thermionic modulator, an impedance in series with each of said tank circuits, a pair of thermionic tubes, means for connecting the internal impedance of one of said tubes in parallel with the impedance in one of said tank circuits and the internal impedance of the other of said tubes in parallel with the impedance of the other of said tank circuits, a source of signal potentials, and means for applying signal potentials from said source to the control electrodes of said tubes in phase opposition.
11. A phase or frequency modulator comprising, a thermionic modulator tube, a source of high frequency oscillations, a tank circuit connected thereto, a pair of tank circuits symmetrically coupled to said first named tank circuit, impedances interposed between each of said pair of tank circuits and the control electrode of said
- thermionic modulator, an impedance in series with each of said tank circuits, a pair of thermionic tubes, means for connecting the anode to cathode impedance of one of said tubes in parallel with the impedance in one of said tank circuits and the anode to cathode impedance of the other of said tank circuits, a source of signal potentials, means for applying signal potentials from said source to the control electrodes of said tubes in phase opposition, and means for tuning each of said pair of tank circuits to a different frequency.
12. Transmitting means comprising, a source of high frequency oscillations, a source of signal potentials, a thermionic modulator tube having a work circuit connected with the output electrodes thereof, a pair of tank circuits, capacitive means for coupling said tank circuits substantially cophasally to the output of said high frequency oscillator, a pair of thermionic tubes, means for connecting the anode to cathode impedance of one of said tubes in series with one of said tank circuits, means for connecting the anode to cathode impedance of the other of said tubes in series with the other of said tank circuits, phase advancing means connecting one of said tank circuits to the control electrode of said thermionic modulator tube, phase retarding means connecting the other of said tank circuits to the control electrode of said thermionic modulator tube, and means for connecting in phase opposition the control electrodes of said pair of tubes to said source of signal potentials.
13. A circuit for modulating the phase of carrier frequency oscillations comprising, a tuned tank circuit adapted to be energized by carrier frequency oscillations, a modulator tube having an output circuit, a control electrode and a cathode, a pair of tank circuits, each comprising an inductance and a capacity in series with a resistance, a coupling between each of said pair of tank circuits and said tuned tank circuit, impedances connecting each of said pair of tank circuits to the control electrode of said modulator tube, a pair of thermionic tubes, each having anode, cathode and control grid, a circuit for connecting the anode to cathode impedance of one of said tubes in parallel with the resistance in one of said tank circuits, a circuit for connecting the anode and cathode impedance of the other of said tubes in parallel with the resistance in the other of said tank circuits, and a source of modulating potentials connected in phase opposition to the control grids of said tubes.
14. A phase modulator comprising, a high frequency oscillator, a thermionic tube having input electrodes, a pair of tank circuits coupled to said oscillator, means for tuning said tank circuits to a harmonic of the frequency of said oscillator, a phase advancing reactance connecting one tank circuit to the input electrodes of said tube, a phase retarding reactance connecting the other tank circuit to the input electrodes of said tube whereby a relative phase shift is produced in the oscillations transferred from said oscillator by way of said tank circuits to the input electrodes of said tube, an impedance variable at signal frequency in each tank circuit, and means connected with said impedances to vary the values thereof alternately at signal frequency to produce variations in the intensity of oscillations transferred to the input electrodes.

- of said tube by way of the respective tank circuits.
15. Phase modulating means comprising, a thermionic tube adapted to repeat high frequency oscillations, said tube having input electrodes, a pair of tank circuits each including series reactances, a source of high frequency oscillations, reactances coupling said source of high frequency oscillations to said reactances in said tank circuits, phase shifting elements connecting each of said tank circuits to the input electrodes of said tube, said aforesaid reactances being of a nature to transfer substantially in-phase oscillations to said phase shifting elements, a variable impedance in each of said tank circuits, and a circuit for varying said impedances at signal frequency, to thereby vary the amount of oscillatory energy reaching the input electrodes of said tubes by way of said respective tank circuits and said phase shifting elements.
16. The combination of a work circuit, a source of high frequency oscillations, a symmetrically grounded tank circuit coupled to said source, an asymmetric translating device connected to said work circuit, a pair of circuits tuned to different frequencies and connected to said translating device, variable couplings between said tank circuits and said source of high frequency oscillations, said tuned circuits and couplings normally transferring phase displaced oscillations to said translating device to produce therein resultant oscillations, and means for varying the response of said tuned circuits to oscillations transferred thereto from said source of high frequency oscillations alternately at signal frequency to thereby vary the phase of the resultant oscillations in said translating device.
17. The combination of a high frequency oscillator, a thermionic repeater having input electrodes and output electrodes, a work circuit coupled to the output electrodes of said repeater, a

pair of tank circuits tuned to different frequencies, said tank circuits being symmetrically coupled to said source of high frequency oscillations, impedances of like character coupling said tank circuits to the input electrodes of said thermionic repeater, and means for varying the impedances of said tank circuits alternately at signal frequency to thereby produce relative phase shifts in the oscillations transferred by said tuned circuits from said oscillator to said repeater.

5

18. The combination as recited in claim 16 in which a frequency multiplier is interposed between said work circuit and said asymmetric translating device.

19. The combination as recited in claim 17 in which an amplitude limiter and frequency multiplier are interposed between said work circuit and said thermionic repeater.

20. A device as recited in claim 17 in which a circuit including reactances tuned to a harmonic of the frequency at which said high frequency oscillator operates is interposed between the output electrodes of said thermionic repeater and said work circuit.

21. A signaling system comprising a phase modulating means as recited in claim 15 in which said thermionic tube has output electrodes in which a circuit tuned to a harmonic of the frequency of the oscillations of said high frequency source is connected to said output electrodes.

25

22. A phase modulating means as recited in claim 15 wherein said phase shifting elements each comprise series tuned reactances.

23. Means for modulating high frequency oscillations as recited in claim 9 wherein said pair of tuned tank circuits are tuned to a harmonic of the high frequency oscillations to be modulated and wherein said impedances each comprise series tuned reactances.

GEORGE L. USSELMAN. 40
